UNITED STATES PATENT OFFICE.

EDMUND TROWBRIDGE DANA MYERS, JR., OF RICHMOND, VIRGINIA.

SMOKE-CONTROL AND DRIFT VALVE MECHANISM.

1,327,404.

Specification of Letters Patent.

Patented Jan. 6, 1920.

Application filed May 26, 1919. Serial No. 299,707.

To all whom it may concern:

Be it known that I, EDMUND T. D. MYERS, Jr., a citizen of the United States, residing at Richmond, in the county of Henrico, State of Virginia, have invented certain new and useful Improvements in Smoke-Control and Drift Valve Mechanism, of which the following is a description, reference being had to the accompanying drawing and to the figures of reference marked thereon.

This invention relates to new and useful improvements in devices for the abatement and control of smoke issuing from the stack of railway locomotives.

My invention has for its object the abatement and control at the will of the engineer of the amount of smoke issuing from the stack to such an extent as to render it practically unnoticeable when passing through tunnels, train sheds, towns, and other places where smoke is now a great nuisance and the sparks a menace, while at the same time permitting the engineer to avail himself of the full force of the draft when the occasion demands.

Another object resides in a construction permitting a moderation of the draft to prevent the jerking from the bed of the fire and the expulsion from the stack by the forced draft, part of the fuel and smoke before it has had time to burn.

Still another object lies in preventing the occurrence of a vacuum in the main cylinders sufficient in extent to draw into the main exhaust passage, the valves and the cylinders cinders, sparks and smoke when the steam is shut off and the locomotive is drifting.

A further object resides in a construction which eliminates the present practice of opening the fire box door when the engine is starting or pulling an extremely heavy load, with the consequent bad effect on the boiler due to the rush of cold air through it.

It will be understood that, when the fire box door is opened, there is a reduction of draft below and through the fire and through the grates because a large part of the air goes through the door and over the top of the fire and does not heat the bed but has a chilling influence upon the flues.

In the drawings, which show by way of

illustration one embodiment of the invention:

Figure 1 is a side elevation of a modern locomotive in dotted outline with my invention applied thereto;

Fig. 2 is an enlarged sectional detail taken through the smoke box and showing the relative arrangement of the main and auxiliary nozzles, the stack and by-pass;

Fig. 3 is a side elevation of the exterior casing and control cylinder and its manner of attachment to the cylinder saddle which is shown in section;

Fig. 4 is a detail sectional view of the auxiliary nozzle and the manner of attaching it to the cylinder saddle;

Fig. 5 is a similar view of the main exhaust nozzle and valve therein;

Fig. 6 is an elevational view of the main nozzle with the valve shown in dotted outline;

Figs. 7 and 8 are detail views of the adjustable bearing for the valve shaft;

Fig. 9 is a sectional detail view of the engineer's control valve; and

Fig. 10 is an elevation of the same taken at right angles thereto.

Locomotives of the present day are provided with an exhaust pipe nozzle communicating with the exhaust from the cylinder. This nozzle is ordinarily attached to the cylinder saddle and is located in the smoke box in a position to discharge directly into the smoke stack for producing a draft in the usual manner. The present invention contemplates a construction in which the single exhaust pipe nozzle is replaced by a double nozzle, the main nozzle of which discharges through the stack, as heretofore, while the auxiliary nozzle has a by-pass connection with the atmosphere so that the steam discharged therethrough produces no draft in the smoke box and stack. Located preferably in this double nozzle is a double valve mechanism adapted in one position to close the auxiliary nozzle which discharges directly to the atmosphere, leaving the main nozzle open; and in its other position to almost entirely close the main nozzle which discharges through the stack and to open the auxiliary nozzle connected with the atmosphere. In the first position the exhaust

80

85

90

95

100

steam passes only through the smoke stack and produces a draft in the usual manner. In the second position of the valve the main body of the steam discharges through the auxiliary nozzle into the atmosphere, thus contributing nothing to the force of the draft, while a small portion of the steam discharges through the almost closed main nozzle, thereby permitting passage of enough steam to cause a small amount of draft through the smoke stack to keep the fire alive and prevent back-draft, but not enough draft to discharge smoke and cinders into the atmosphere in sufficient quantity to be noticeably objectionable.

For the purpose of operating the valve mechanism in the nozzle, there is provided a steam operated valve controlling means consisting of a cylinder, the piston of which is attached to the valve mechanism, while the cylinder chamber is connected by means of a conduit to an engineer's control valve preferably in the cab and operated by hand lever in convenient reach of the engineer. The three ports in this control valve connect the control cylinder with the boiler and the atmosphere, respectively, and the piston therein is provided with ports to effect in one position connection from the boiler to the operating cylinder; and in the opposite position connection from the operating cylinder to the atmosphere.

In addition to the hand lever for operating the control valve to open or close the nozzle valves, there is provided a special connection between the control valve and the engineer's throttle lever consisting of a telescoped bar and spring construction permitting an opening movement of the throttle independent of the control valve but arranged to operate the control valve to close the main exhaust nozzle and open the auxiliary by-pass nozzle when the throttle is closed, so that the suction caused by the reciprocating motion of the main piston draws from the clean atmosphere backward through the vapor exhaust pipe, and not, as at present, from the smoke box laden with cinders, sparks and smoke. The amount of air sucking through the perforations in and the annular space surrounding the valve in the main exhaust nozzle is negligibly small. Thus, the wear of the valve chests, pistons and cylinders, due to the presence in them of the cinders, sparks and smoke, is prevented.

The invention in its preferred form contemplates a double exhaust nozzle adapted to be attached to a boss 1 on the cylinder saddle 2 and communicating with the steam exhaust ports 3 therein. Since this double nozzle is used to replace the single nozzle of the present day use, the usual hold-down bolts 4 are used. At the front of the nozzle these bolts 4 thread directly into the boss 1, as shown in Fig. 5, and at the rear they pass through

steel pads or filling blocks 5, through the walls 6 of the smoke box, and into the cylinder saddle 2. The steel pads are provided to fill the space between the lower wall of the auxiliary nozzle, hereinafter described, and the lower wall of the smoke box which is seated on the cylinder saddle.

The preferred form of nozzle includes an integral casting consisting of a main nozzle 7 and an auxiliary nozzle 8 to which is fastened by bolts 9 on its upper side a corresponding double exhaust pipe consisting of a main exhaust 10 and an auxiliary exhaust 11 which form a continuation of the nozzles. The main nozzle 7 is arranged to create the usual draft, as heretofore, by discharging directly into the stack 12 in the smoke box which is of the usual type.

In order to discharge the steam from the auxiliary nozzle 8 directly to the atmosphere without creating a draft through the stack 12, there is connected to the exhaust pipe a by-pass pipe 13 which has a sliding fit in a flanged seat 14 in the upper mouth of the auxiliary exhaust pipe 11. This by-pass 13 projects through the wall 6 of the smoke box to the rear and lower than the stack mouth, and is preferably bolted in place by a ring 15 which is in turn riveted to the by-pass pipe. The by-pass pipe 13 may discharge to any other convenient place without the smoke box, such as in front of the stack 12.

For the purpose of controlling the flow of steam through the main and auxiliary nozzles, there is provided in the main nozzle a valve 22 and in the auxiliary nozzle a valve 26 preferably arranged on a common shaft 16, which in the present construction has its bearings 17 in the thickened walls of the exhaust nozzle and exhaust pipe. At the rear, the walls of the auxiliary nozzle and exhaust pipe are extended to provide a casing 18 to exclude from the valve mechanism the cinders, smoke and sparks passing through the smoke box. The rearward end of the valve shaft is extended into this casing 18 for a purpose hereinafter described and has an adjustable bearing 19 in the walls thereof similar to the bearing at the other end of the valve shaft. As illustrated in Figs. 7 and 8, the bearings 17 and 19 of the valve shaft are provided with brass bushings 20 which may be adjusted by means of set screws 21 to the desired degree of tightness to prevent lost motion of this shaft.

The valves 22 and 26, which are preferably arranged on the common shaft 16 at an angle of 90° to each other so that one closes as the other opens, and vice-versa, on rotation of the shaft, are similar in design and operation except that the valve 22 controlling the steam flow through the main nozzle 7 is provided with a series of staggered perforations 23 adapted to permit a slight amount of steam to pass therethrough when the valve 130

is in closed position. In addition, there is a slight clearance 24 between the edge of the valve and the walls of the exhaust nozzle 7 and exhaust pipe 10 which affords egress of 5 steam. This main exhaust valve, when in open position, is adapted to form a continuation of the usual baffle plate 25 formed in the exhaust passage.

While these valves 22 and 26 are shown as 10 of the present design and operated from the common shaft 16, it is obvious that any suitable design of valve to accomplish the same function may be used, and it is also patent that with modifications within the scope of 15 the invention these valves may be independently operated or located in any convenient part of the exhaust passages.

The means for operating the valve shaft 16 comprises a control cylinder 27 adapted to 20 be screwed into the wall 6 of the smoke box, preferably to the rear of the cylinder saddle 2, and said cylinder 27 is held in this position by a threaded flange 28. As shown more particularly in Fig. 2, the inner end 25 29 of this cylinder threads into the rearward extension of the nozzle which forms the cinder-proof casing 18 for the connection between this cylinder 27 and the valve shaft 16. Adapted to reciprocate in this cylinder 30 is a piston 30 provided with suitable connections, such as the rod 31, to the crank 32 on the extension of the valve stem 16. In order to limit the inner stroke of this piston 30, there is attached within the cylinder 27 35 at its inner end by bolts 32 or other means a stop, preferably in the form of a circular block 31' provided with concentric bore for permitting the piston rod connection to reciprocate in the cylinder wall. In the space between the fixed block and the head of the 40 piston is arranged a coil spring 33 for the purpose of returning the piston 30 to its normal outward position in the cylinder 27 when the device is not in use. The head of the 45 cylinder is preferably closed by a screw threaded cap 34 provided with a drain hole 35 for discharging the water condensed from the steam. In case air is used as the pressure medium, this drain hole may be omitted. 50 A small steam trap (not shown) may be attached to the drain hole 35 to prevent escape of steam but permit drainage of condensation.

In order to operate the piston in this control cylinder, the lower portion of the inner operating chamber thereof is provided with a pressure conduit 36 to an engineer's control valve, preferably located in the locomotive cab, see Fig. 1. As disclosed in Fig. 9, the 55 details of this valve include a cylinder member 37, the walls of which are provided with three centrally arranged ports into which are threaded pipes connecting to the atmosphere 38, to the source of pressure 39, preferably the engine boiler in this case,

and to the control cylinder 36 heretofore described.

Adapted to be reciprocated within this cylinder 37 is a control valve 40 provided at one end with a projection 41 to limit its outward stroke. To the other end of this valve is attached the valve stem 42 projecting through a closing cap 43 having an exterior annular wall 44 forming a seat for the reception of packing material 45 which, in 70 connection with a steel washer 46 and a threaded nut 47, form a pressure tight packing for the valve stem 42 which is adapted to be reciprocated therethrough. The valve itself is provided at its inner end with a 75 channel 48 which, when the valve is in its extreme outer position, connects the pressure pipe 39 with the pipe connecting with the control valve cylinder 27 to operate the piston 30 therein. The central portion of the 80 valve is provided with a channel portion 49 which does not extend entirely around the valve and is adapted to connect the control cylinder 27 with the conduit 38 leading to the atmosphere, whereby permitting the 85 spring 33 to return the piston 30 to its normal outer position. Preferably cored in the walls of the control valve cylinder are conduits 50 leading from the inner extremities 90 of the valve cylinder to the port 38 connected with the atmosphere so that there will be no backing up of pressure in front of the valve 95 40 as it advances in either direction. In order to normally force the valve to its innermost position, shown in Fig. 9, there is 100 arranged in the outermost portion of the valve cylinder and surrounding the projection 41 on the outer face of the piston, a circular spring 51.

For operating at will the control valve 40, 105 there is provided a hand lever 52 connected at 53 to the extension of the valve rod 42, and this lever 52 in turn is pivoted, as at 54, to an arm 55 adapted to be attached to any convenient stationary member, herein shown 110 as the control cylinder 37. In addition to the lever 52 for operating at will the control valve 40, there is also provided a special connection to the engineer's throttle valve. This connection takes the form of a 115 hollow sleeve 56 adapted to be secured in any suitable manner to the extreme end of the valve rod 42. This sleeve 56 receives the telescoping member 57 which is pivotally connected to the engineer's throttle lever 59 120 located as usual in the cab as shown in Fig. 1. Within the sleeve 56, between the end of the valve rod 42 and the telescoping member 57, there is arranged a spring 58 to take up lost motion and prevent shock to the piston of the control valve when moved by the closing of the throttle valve. This telescopic connection provides means whereby the inner or closing movement of the throttle valve will operate the control valve 40, 125 130

whereas the reverse or opening movement of the throttle valve will have no effect upon it.

Operation.

5 In operation, starting with the throttle lever 59 in closed position, by means of the telescopic spring connection, the hand lever 52 and hence the control valve 40 are normally forced to the right against the action of the spring 51 in the control cylinder 37. In this position of the valve, steam from the boiler is admitted through the conduit 36 into the valve operating cylinder 27 to 10 force the piston 30 therein upwardly against the action of the spring 33 to close the main nozzle valve 22 and open the auxiliary nozzle 26. In the initial starting, the engineer grasps the hand lever 52 and holds it from 15 being forced to the left by spring 51, when the throttle is opened. Immediately he opens the throttle 59. The steam will now flow in two directions: first, through the small holes 23 in the main exhaust valve 22, as well as through the small annular space 24 between the periphery of the valve 22 and the walls of the exhaust pipe 7, so 20 as to permit the passage of enough steam to cause a small amount of draft through the stack 12 to keep the fire alive and prevent back-draft, but not enough to discharge smoke and cinders into the atmosphere in sufficient quantity to be noticeably objectionable; and second, the main body of steam 25 will pass through the auxiliary nozzle 11 and into the atmosphere, thus contributing nothing to the force of the draft and preventing back pressure into the main steam cylinders. This arrangement of the valves 30 is particularly desirable in starting the locomotive since the excessive draft usually produced by the full discharge of steam through the stack is avoided. Experience 35 has shown that such a draft has a tendency 40 to pull the bed of fire to pieces, and to expel through the stack part of the unburnt fuel and combustion products.

At the desired time, should the engineer wish to avail himself of the draft created 45 by the full force of the steam discharging through the stack 12, he releases his hold on the hand lever 52 which, by reason of the spring 51 in the valve cylinder 37, will move the valve 40 to its other extreme position 50 in the valve cylinder 37, thus throwing the hand lever 52 to the left, as shown in Fig. 9. In this position, the valve 40 connects the valve operating cylinder 27 with the atmosphere so that the spring 33 in the cylinder 27 forces its piston 30 down, rotating the valve 22 in the main exhaust, whereby all 55 of the steam is discharged into the stack 12.

When the engineer closes his throttle and the locomotive begins to drift, the telescopic

connection 56, 57 and 58 between the throttle 65 lever 59 and the control valve 40 immediately operates the latter against the action of the spring 51 in the valve cylinder, thus supplying steam to the control cylinder 27 to close the valve 22 in the main exhaust 70 pipe 10 and open the valve in the auxiliary exhaust pipe 11. In this position of the valves with the steam shut off, the suction caused by the reciprocating motion of the main pistons draws from the clean atmosphere backward through the auxiliary pipe 13 and not as at present from the smoke box laden with cinders, sparks and smoke. The amount of air sucked through the perforations 23 in and the annular space 24 75 surrounding the valve 22 in the main exhaust pipe is negligibly small. Thus the cutting of the valve chests, pistons and cylinders due to the presence in them of cinders, sparks, and smoke is prevented. Obviously it is within the contemplation of this invention to provide the hand lever 52 operating the control valve with means to hold it in both or in either extreme position, but the device is preferably operated 80 without such an attachment.

Having thus described my invention, what I claim as new and desire to secure by Letters Patent, is:

1. In a device of the character described, in combination with the stack, the cylinder saddle and smoke box of a locomotive, a draft device therefor comprising a steam exhaust nozzle adapted to be attached to the cylinder saddle and communicating with the usual cylinder exhaust ports therein, said nozzle including a main nozzle discharging directly into the stack and an auxiliary nozzle, a steam by-pass connection from said auxiliary nozzle to the atmosphere, and 100 separate means for controlling the discharge of steam through each nozzle, said means being operable at will.

2. In combination with the smoke box, stack and cylinder saddle of a locomotive, a draft device therefor including means connected with the usual cylinder steam exhaust ports adapted to discharge the steam directly into the stack, means also connected with said exhaust ports and adapted to discharge steam into the atmosphere independently of said stack, and separate means operable at will for controlling the flow of steam through each of said first mentioned steam discharging means.

3. In combination with the smoke box, stack and cylinder saddle of a locomotive, a draft device therefor including means connected with the usual cylinder steam exhaust ports adapted to discharge the steam directly 110 into the stack, means also connected with said exhaust ports and adapted to discharge steam into the atmosphere independently of 115

120

125

said stack, and valve mechanism for each steam discharging means operable at will for controlling the flow of steam therethrough.

65 valve operating cylinder, and means for operating said valve to connect said cylinder with either the source of pressure or the atmosphere.

8. In combination with the smoke box, stack and cylinder saddle of a locomotive, a draft device therefor including means connected with the usual cylinder steam exhaust ports adapted to discharge the steam directly into the stack, means also connected with said exhaust ports and adapted to discharge steam into the atmosphere independently of said stack, a valve for each of said steam discharging means to control the flow of steam therethrough, and means for operating said valves at will. 70
